US00D702618S

(12) **United States Design Patent**
Avasiloiae et al.

(10) **Patent No.:** **US D702,618 S**
(45) **Date of Patent:** **** Apr. 15, 2014**

(54) **WIPER BLADE COUPLER**(71) Applicant: **Trico Products Corporation**, Rochester Hills, MI (US)(72) Inventors: **Valentin Avasiloiae**, Dearborn Heights, MI (US); **Daniel Ehde**, Ortonville, MI (US)(73) Assignee: **Trico Products Corporation**, Rochester Hills, MI (US)(***) Term: **14 Years**(21) Appl. No.: **29/437,314**(22) Filed: **Nov. 15, 2012**(51) **LOC (10) Cl.** ..... **12-06**(52) **U.S. Cl.**USPC ..... **D12/220**(58) **Field of Classification Search**

USPC D12/219-220; 15/246, 247, 250.1, 15/250.4, 250.361, 250.19, 250.48, 15/250.03, 250.31-250.33, 250.201, 15/250.451, 250.458, 250.04, 250.07, 15/250.44

(57) **CLAIM**

The ornamental design for a wiper blade coupler, as shown and described.

DESCRIPTION

FIG. 1 is a perspective view of the wiper blade coupler design of the present invention;

FIG. 2 is a top view thereof;

FIG. 3 is a left side view thereof;

FIG. 4 is a right side view thereof;

FIG. 5 is a bottom view thereof;

FIG. 6 is an end view thereof; and,

FIG. 7 is a view of the opposite end thereof.
